UNITED STATES PATENT OFFICE.

ARTHUR STOCKSTROM, OF ST. LOUIS, MISSOURI, ASSIGNOR TO AMERICAN STOVE COMPANY, OF ST. LOUIS, MISSOURI, A CORPORATION OF NEW JERSEY.

DESIGN FOR A GAS HEATER.

Application filed August 1, 1922. Serial No. 3,262. Term of patent 14 years.

To all whom it may concern:

Be it known that I, ARTHUR STOCKSTROM, a citizen of the United States, residing at St. Louis, in the State of Missouri, have invented a new, original, and ornamental Design for Gas Heaters, of which the following is a specification, reference being had herein to the accompanying drawings.

The accompanying drawing is a front view of a gas heater.

What I claim is:

The ornamental design for a gas heater, as shown.

In testimony whereof, I hereunto affix my signature.

ARTHUR STOCKSTROM.
